UNITED STATES PATENT OFFICE

OLIVER C. SIMMS, OF WILLISTON PARK, NEW YORK

DESIGN FOR A RADIO BENCH OR THE LIKE

Application filed December 1, 1930. Serial No. 37,851. Term of patent 3½ years.

To all whom it may concern:

Be it known that I, OLIVER C. SIMMS, a resident of Williston Park, county of Suffolk, and State of New York, whose post-office address is 13 East 17th Street, New York city, New York, a citizen of the United States, have invented a new, original, and ornamental Design for a Radio Bench or the like, of which the following is a specification, reference being had to the accompanying drawing, forming part thereof, wherein—

I claim:

The ornamental design for a radio bench or the like, as shown.

OLIVER C. SIMMS.
